William M. Wilcox,
BY *Frank A. Lehman.*

ATTORNEY.

UNITED STATES PATENT OFFICE.

WILLIAM MARION WILCOX, OF ELBERTON, GEORGIA.

SPARK-PLUG TERMINAL.

Application filed November 1, 1927. Serial No. 230,274.

This invention relates to terminals for electrical conductors or contacting means between an electric terminal and a conductor.

5 It is an object of this invention to provide a novel contact or bearing plate to be associated with conductors and terminals, effective to increase the size of the path of travel for current and to insure a metal to metal contact, free of coatings which might retard the passage of current.

It is furthermore an object of the invention to provide a device of this character which will aid in retaining a binding nut 15 properly set with respect to the said conductor.

It is a further object of this invention to produce a contact plate to be associated with a conductor tip in which a "wiping" action 20 is effected when the conductor tip and contact plate are assembled, to insure the aforesaid metal to metal engagement of the elements for increasing the efficiency.

It is furthermore an object to produce a 25 contact plate and a conductor tip which, in their assembled state, may be applied to a binding post or a spark plug electrode prior to the application of the binding nut to the said post or electrode.

30 With the foregoing and other objects in view, the invention consists in the details of construction, and in the arrangement and combination of parts to be hereinafter more fully set forth and claimed.

35 In describing the invention in detail, reference will be had to the accompanying drawing forming part of this application, wherein like characters denote corresponding parts in the several views, and in which—

40 Figure 1 illustrates a view in elevation of a spark plug showing a device embodying the invention applied thereto;

Figure 2 illustrates a sectional view of the contact plate prior to its being shaped as 45 it is shown in Fig. 1;

Figure 3 illustrates a sectional view of an assembly having a slightly modified construction;

Figure 4 illustrates a plan view of the 50 plate;

Figure 5 illustrates a plan view of the contact plate and conductor tip associated with a terminal; and

Figure 6 illustrates a perspective view of 55 a fragment of the contact plate exaggerated

to show the burr formed when the plate is punched.

In these drawings, 10 denotes a spark plug which may be of any conventional type, 11 a conductor of approved type, and 12 a terminal tip comprising an apertured plate with appropriate means for attaching or anchoring it to the conductor. As the manner of connecting the plate and conductor may be changed to suit particular requirements, the inventor does not wish to be limited with respect to the manner of accomplishing the foregoing. The contact plate which is employed in association with the conductor terminal in the form shown in 60 Figures 1 and 2 comprises a plate having apertures 14 and 15 near each end which are intended to register or aline when the plate is doubled on itself, as shown in Fig. 1, and the said apertures are also intended to 65 aline with an aperture 16 formed in the conductor tip, and the said alined apertures are intended to receive a binding post or electrode.

The conductor plate and terminal tip are, 70 of course, assembled prior to their being applied to the binding post and, in assembling them, the plate and tip are moved for the purpose of inserting the tip between the parallel portions of the plate. Preferably 75 the space between the parallel portions of the plate is normally slightly less than the thickness of the tip and, therefore, friction develops when the tip and plate are assembled, resulting in a wiping action which 80 serves to dislodge grease or coatings from the contacting surfaces, and this results in increasing the conductivity of the assembly, as compared with that which would occur should there be interposed deposits of 85 grease or other foreign substances. The plate also acts as a washer which will prevent movement of the tip being communicated directly to the nut and, in practice, this 90 has been found to cause the nut to hold on 95 the threads to better advantage.

In the modifications illustrated in Figs. 3, 4 and 5, the plate 17 is shown as having a burr 18 around each of the apertures 19, this burr being formed when the plate is 100 punched to form the said holes 19. It is well known, of course, that punching can be done without producing a burr and it can also be done by producing a burr. When this modified form of the invention is adopted, 105 110

it has been found that the serrations of the burr escape the surface of the tip and that they dislodge deposits on the tip to better advantage and insure a metal to metal contact which increases the conductivity of the assembly, and the burr can be so formed as to produce a yielding resistance to the binding nut, which will increase the friction between the threads of the binding nut and 10 post.

I claim:

An assembly for electrical connections comprising a plate doubled on itself and separable from a coacting conductor, the superimposed portions of the plate having coinciding apertures adapted to receive an electric terminal, and a conductor tip fitted between the superimposed portions of the plate and having an aperture coinciding with the apertures of the plate. 15

WILLIAM M. WILCOX.
